SHUTTLE WITHDRAWING DEVICE

Filed Feb. 13, 1925

Fig. 3.

UNITED STATES PATENT OFFICE.

PHILIP D. DOHERTY, OF WORCESTER, MASSACHUSETTS, ASSIGNOR TO CROMPTON & KNOWLES LOOM WORKS, OF WORCESTER, MASSACHUSETTS, A CORPORATION OF MASSACHUSETTS.

SHUTTLE-WITHDRAWING DEVICE.

Application filed February 13, 1925. Serial No. 8,994.

To all whom it may concern:

Be it known that I, PHILIP D. DOHERTY, a citizen of the United States, residing at Worcester, in the county of Worcester and State of Massachusetts, have invented a new and useful Shuttle-Withdrawing Device, of which the following is a specification.

This invention relates to improved means for enabling a weaver to withdraw a shuttle from the box of a loom and one object of the invention is to provide such a device which can be actuated by a connection to the usual picking mechanism.

Another object of the invention is to provide a shuttle withdrawing device conveniently located to be operated by foot power so as to leave the weaver's hands free to manipulate the shuttle.

A still further object of the invention is to provide a shuttle withdrawing device associated with the picking mechanism of a loom and normally in inoperative position but movable through a slight angle to be effective to actuate the picking mechanism at the will of the operator and independently of the loom drive.

With these and other objects in view, which will appear as the description proceeds, my invention resides in the combination and arrangement of parts hereinafter described and set forth in the claims.

In the accompanying drawings wherein I have shown a convenient embodiment of my invention,

Fig. 1 is a front elevation of one end of a loom having my invention applied thereto showing the device in normal inoperative position.

Fig. 2 is a view similar to Fig. 1 but showing the device depressed to withdraw a shuttle,

Fig. 3 is an end elevation of the structure shown in Fig. 1,

Fig. 4 is a horizontal section taken on line 4—4 of Fig. 3,

Fig. 5 is an enlarged section on line 5—5 of Fig. 1, and

Fig. 6 is a section on line 6—6 of Fig. 5.

Referring more particularly to the drawings it will be seen that I have provided a loom frame 10 having mounted on the lower end thereof a rocker shaft 11 to which is secured a picker foot 12. A picker stick 13 is pivotally connected to the foot 12 and

as shown in the present instance passes 55 through a slot 14 in the lay 15. The lay is provided with a box 16 which receives the shuttle S and is mounted on swords one of which is indicated at 17.

The mechanism for giving motion to the 60 picker stick 13 comprises a picking shaft 18 extending substantially parallel to the frame 10 and supported by bearings one of which is indicated at 19. Secured to the shaft 18 is a picking arm 20 the upper end 65 of which is operatively connected to sweep stick 21, the outer end of said sweep stick being provided with a lug strap 22 which passes outside the picker stick 13 and is positioned vertically by means of holder 23. 70 By means of mechanism not shown the shaft 18 is given periodic oscillations in a left hand direction as viewed in Fig. 1 the effect of which is to draw the picker stick 13 to the left to expel the shuttle S from the 75 box 16. A return spring 24 may be provided to restore the picker stick to normal position. The matter thus far described is well known in the art and forms no part of my present invention.

In carrying out my invention I extend the shaft 18 and pass the same through an auxiliary forward bearing 30 having a horizontal foot 31 which is adjustably secured to an upstanding brace 32 which is bolted 85 to the cross girder 33 by bolts 34. The auxiliary bearing 30 has an offset forwardly extending horn 35 for a purpose to be described. As shown in Fig. 5 I provide a sleeve 36 which is connected by means of a 90 key 37 to the picking shaft 18 and held against longitudinal movement on the shaft 18 by a set screw 38 which is threaded into the sleeve and engages said shaft. A foot lever 39 having a treadle 40 is provided 95 with a bearing or hub 41 which is loosely mounted on the sleeve 36 and is located between the set screw 38 and a flange 42 formed on the auxiliary bearing 30. In this way the foot lever is positioned with respect to 100 the picker shaft and is free to be moved around the same as a center. A spring 43 is interposed between the foot lever 39 and the horn 35 for the purpose of holding the foot lever in normally raised position.

As shown more particularly in Fig. 6 the sleeve 36 is provided with a lug 44 and the hub 41 of the foot lever is provided with a

boss 45 which is in alignment with the lug 44. The parts are so proportioned and the action of the spring 43 is such that the boss 45 is normally slightly spaced from the lug 44. This construction is desirable inasmuch as lug 44 is splined on the picker shaft and moves therewith during the normal operation of the loom.

Under normal conditions the shaft 18, 10 sleeve 36, and lug 44 will vibrate without contact with the boss 45 but when the loom stops and it is desirable to remove the shuttle for any reason the foot lever 39 will be depressed to assume the position shown in 15 Fig. 2, the effect of which is to cause boss 45 to engage lug 44 and move the latter in a counter-clockwise direction causing the picker stick to eject the shuttle from the box. The foot lever is then released and the 20 spring 43 serves to return the same and boss 45 to normal position and spring 24 will return the picker stick to its normal position carrying with it the lug 44.

From the foregoing it will be seen that I 25 have provided a very simple means for ejecting a shuttle from the box of a loom by operating upon the usual picking motion and that the operating parts when in normal position are spaced so as to avoid interference with the usual picking motion of the loom. It will furthermore be noted that the hub of the foot lever is confined in a convenient manner.

Having thus described my invention it 30 will be apparent that changes and modifications may be made therein by those skilled in the art without departing from the spirit and scope of the invention, and I do not wish to be limited to the details herein disclosed but what I claim is:

1. In a loom having a shuttle box and a shuttle therein, a picker stick, loom actuated means to give said stick regular shuttle ejecting movements, and a manually operable device normally in inoperative position but movable to impart motion to said loom-actuated means to give the picker stick a shuttle ejecting movement.

2. In a loom having a shuttle box and a shuttle therein, a picker stick to eject the shuttle from the box, operating mechanism connected to the picker stick, a normally inoperative manually actuable device movable at the will of the operator to operative relationship with the operating mechanism to give the picker stick a shuttle ejecting movement.

3. In a loom having a shuttle box and a shuttle therein, a picker stick to eject the 60 shuttle from the box, a picker shaft, con-

nections from the picker shaft to operate the picker stick, and a manually actuable device supported by the picking shaft, said device being normally in inoperative position and movable at the will of the operator to operative position to actuate the picker shaft and cause the picker stick to have a shuttle ejecting movement.

4. In a loom having a shuttle box and a shuttle therein, a picker stick, a picker shaft, 70 connections between the picker shaft and the picker stick to give said picker stick a shuttle ejecting movement, a member secured to the shaft and having a lug thereon, a manually operable lever loosely mounted with respect to the picker shaft and having a boss thereon in alignment with the lug, said boss being normally out of the path of the movement of said lug as the latter moves with the picker shaft, said boss being movable at 80 the will of the operator into operative engagement with the lug to give said picker shaft and picker stick a shuttle ejecting movement.

5. In a loom having a shuttle box and a shuttle therein, a picker stick, a picker shaft, connections between the shaft and the picker stick to give the picker stick a shuttle ejecting movement when the picker shaft has an operative vibration, a sleeve secured to the 90 shaft, a lug carried by the sleeve and movable therewith, a foot lever having a hub loosely mounted on the sleeve, a boss carried by the hub in substantial alignment with the lug, yielding means to hold said boss normally out of operative relationship with respect to the lug, said foot lever being depressible to cause engagement between the lug and the boss to give the picker stick a shuttle ejecting movement.

6. In a loom having a shuttle box and a shuttle therein, a picker stick, a picker shaft, connections between the picker stick and the picker shaft to give said picker stick a shuttle ejecting movement when the picker shaft receives an operative vibration, a sleeve 105 mounted on the picker shaft, means to secure the sleeve to the shaft including a radially extending member, a bearing for said shaft, a foot lever having a hub mounted loosely on said sleeve and positioned by the radially extending member and the bearing, and interengaging devices formed on the sleeve and hub normally in inoperative position but movable at the will of the operator to give 115 said sleeve and shaft an operative vibration.

In testimony whereof I have hereunto affixed my signature.

PHILIP D. DOHERTY.
